UNITED STATES PATENT OFFICE.

FREDERICK W. BOLD, OF CHELSEA, MASSACHUSETTS, ASSIGNOR TO CHARLES H. PEARSON, OF BROOKLINE, MASSACHUSETTS.

FUSE.

Original application filed January 2, 1925, Serial No. 285. Divided and this application filed December 4, 1925. Serial No. 73,276.

My present invention relates to mechanical time fuses, and more particularly to an improved means for operatively connecting the timing train with the setting disc.

5 In the patent granted to me No. 1,569,911 and dated January 19, 1926, for an improvement in release levers for mechanical time fuses, I have disclosed the connecting means for operatively connecting the timing train 10 and the setting disc forming the subject matter of the present invention, and my present application is, therefore, to be considered as a divisional of said prior patent. In order to set the timing train of a mechanical time fuse with the setting disc to detonate at a predetermined time after the shell to which the same is attached is put in flight it is necessary to have such an operative connection between the driving train 20 and the timing mechanism that will allow relative movement therebetween during the setting operation and up to the instant that the shell to which the same is attached is put in flight. Further, it is important and desirable 25 that means be provided for preventing longitudinal or axial movement of the connecting means with respect to each other while yet permitting relative movement thereof, the means for preventing axial 30 movement acting as a means for preventing a progressive "drifting" of the parts due to relatively slight shocks being given to the apparatus. In carrying out my invention I arrange between the staff of the timing train 35 and the sleeve associated with the driving spring of the timing train a circumferential groove into which loosely fits a projecting point or a plurality of points on the sleeve of the driving spring. This construction 40 permits relative rotative movement of the staff and sleeve and prevents longitudinal movement of the staff and sleeve and attached parts with respect to each other and thereby prevents locking together of the 45 sleeve and staff by any shock less than the shock of firing.

The object of my invention, therefore, is an improved means for operatively connecting the timing train and the setting disc 50 of a mechanical time fuse.

In the accompanying drawings illustrating the preferred embodiment of my invention,

Fig. 1 is a detail central sectional elevation

through a portion of a mechanical time fuse; 55

Fig. 2 is an enlarged sectional elevation of a portion of Fig. 1, and

Fig. 3 is a sectional elevation on the line 3-3 of Fig. 2.

Referring to the drawings, there is illustrated a timing train consisting of various mechanisms mounted on a bottom plate 10, middle plate 11, and top plate 12, these plates being spaced apart from each other in the usual manner. Rotatably mounted 60 in the middle plate 11 and top plate 12 is a central staff 13, which is provided intermediate its ends with a circumferential groove 14. The lower end of the staff 13 is wedge-shaped, as clearly shown in Fig. 1, 70 and rotatably mounted on such central staff is a sleeve 15. While the sleeve 15 is rotatably mounted on the staff 13, it is prevented from longitudinal movement thereon under ordinary conditions by the projections 16 75 extending into the circumferential groove 14 and formed in such sleeve by prick punching or in any other suitable manner. These projections 16 are sufficient to prevent longitudinal movement of the sleeve 15 on the 80 staff 13 under ordinary conditions but, on the shock of firing, the sleeve 15 will drift and wedge onto the wedge-shaped portion at the lower end of the staff 13 thereby rigidly locking the sleeve 15 and the center staff 85 13 together. Secured to the upper end of the staff 13 is a setting plate 17 and by means of which the relative position of the staff 13 and gear 18, that is secured to the lower end of the sleeve 15, is varied. The sleeve 90 15 is slidably mounted in a sleeve 19 to which the inner end of the driving spring 20 is secured. Longitudinal movement of the sleeve 15 with respect to the staff 13 may take place without disturbing the position of the driving spring 20 with relation to the other parts of the device. 95

By my device it will be obvious that independent rotative movement of the sleeve 15 and staff 13 may take place and that, 100 by virtue of the circumferential groove 14 and inwardly extending projection 16, longitudinal movement of the sleeve 15 and staff 13 is prevented. As it will be impossible to lock the sleeve 15 and staff 13 together until relative downward movement of the sleeve 15 takes place with respect to the staff 13, and as such relative movement can only 105

take place on the shock of firing, there is no danger of such elements being locked together by any other means. This device, therefore, constitutes a distinct safety feature for mechanical time fuses.

Having thus described my invention, what I claim as new is:

1. In a time fuse, the combination of a timing train, a sleeve associated therewith and movable relatively thereto, a staff, means thereon for transmitting power to the timing mechanism, and means associated with said staff and said sleeve for permitting locking of the sleeve and the staff together on the shock of firing.
2. In a time fuse, the combination of a timing train, a spring driving motor for transmitting power to the timing train, a sleeve associated with the driving motor, a staff associated with the timing train, a circumferential groove formed in said staff,

and means formed integral with said sleeve and projecting inwardly therefrom into the circumferential groove whereby rotative movement of the sleeve on the staff is permitted and longitudinal movement of said sleeve is prevented under normal conditions of operation.

3. The combination with a timing train, of a sleeve associated therewith and movable axially with respect thereto, a staff on which said sleeve is mounted, a circumferential groove formed on the staff, and a member formed on the interior of the sleeve and projecting into said groove whereby rotary movement of the sleeve and staff is permitted and longitudinal movement prevented under normal conditions of service.

In testimony whereof, I have signed my name to this specification.

FREDERICK W. BOLD.
